UNITED STATES PATENT OFFICE.

HARRY LANDSIEDEL, OF POPLAR BLUFF, MISSOURI, ASSIGNOR, BY MESNE ASSIGNMENTS, TO THE DALTON ADDING MACHINE COMPANY, OF CINCINNATI, OHIO, A CORPORATION OF OHIO.

RECORDING-MACHINE.

1,142,787.

Specification of Letters Patent.

Patented June 8, 1915.

Application filed September 5, 1913. Serial No. 788,233.

To all whom it may concern:

Be it known that I, HARRY LANDSIEDEL, a citizen of the United States, residing in the city of Poplar Bluff and State of Missouri, have invented a new and useful Recording Machine, of which the following is a specification.

This invention relates to recording machines, and has particular reference to the mechanism for adjusting and retaining the paper in proper position.

The invention consists of an improved clutch device coöperatively combined with the platen which holds and feeds the paper, whereby the paper may be adjusted with precise accuracy to any required position, whenever it is desired to adjust the paper with exactness for receiving records on predetermined lines.

An object of the invention is to combine with the paper platen a positive and accurate clutch for holding the platen in any desired adjustment with respect to the paper feeding or platen rotating devices, so that when the platen has been adjusted to hold and feed the paper as desired it will be impossible for the platen to move, with respect to the paper feeding device as sometimes occurs on machines at present in use, resulting in improper alinement of the records on the paper.

The broad object of the invention is to provide an improved clutch device operable to turn the platen to position any selected part of the paper at the recording line and adjustable in connection with the paper feeding device to prevent displacement of the paper.

Another object is to provide a clutch device in connection with the platen, and a platen rotating knob operable to rotate the platen, and automatic means for engaging the clutch device to hold the platen from accidental rotation.

Other objects will appear from the following detail description, reference being made to the accompanying drawings in which I have illustrated one embodiment of my invention, and in which—

Figure 1 is a side elevation of a "Dalton" adding and recording machine having my invention combined therewith for purposes of illustration. Fig. 2 is an enlarged longi-

tudinal sectional view of the clutch mechanism taken parallel with the platen shaft and illustrating the clutch closed. Fig. 3 is a similar sectional view illustrating the clutch open. Fig. 4 is a cross sectional view approximately on the line 4—4 of Fig. 3. Fig. 5 is a diagrammatic view illustrating a possible relative arrangement of the teeth on the coöperating clutch members—it being understood that the relative arrangement of the teeth may be varied in conformity with the number of the teeth employed, or in conformity with the size of teeth, or in accordance with other conditions. Fig. 6 is a front elevation of the platen and carriage with my invention combined therewith, and mounted upon a "Dalton" adding machine. Fig. 7 is a detail view of the detent and line space wheel by which the platen is rotated when the clutch is closed and which is arranged to coöperate with the clutch when the clutch is opened to hold the detent firmly seated upon the line space wheel with which the detent coöperates.

The platen 1 is mounted in a carriage 2 and is supported upon a shaft 3 which is journaled in bearings in the side frames of the carriage.

A knob 4 (Fig. 6) is attached to one end of the shaft 3 for adjustment and manipulation of the platen and carriage. The clutch and line space wheel are mounted upon the opposite end of the shaft.

The line space wheel 5 is loosely mounted upon the platen shaft 3 and is engaged by a detent 6 supported by a lever 7 which is pivoted to the side of the carriage. The lever 7 is in the form of a bell crank and is actuated by a spring 8, one end of which is connected to a depending arm of the lever and the other end of which is connected to the side of the carriage effectively to actuate the detent 6 in engagement with the wheel 5. Thus the wheel will be retained in its different line space adjustments which conform to the distances between the teeth on the periphery of said wheel.

As above stated, the wheel 5 is loosely mounted on the shaft 3. Said wheel is provided with a number of studs 9, (Figs. 2 and 3) which extend through holes in one of the clutch members 10 and thereby interlock said wheel and said clutch member, so

that the clutch member will be driven with the wheel.

A coil spring 11 encircles the shaft 3 between the clutch member 10 and the wheel 5 thereby actuating said clutch member away from said wheel effectively to engage said clutch member with the coöperating clutch member, as hereinafter described. The clutch member 10 is provided with an outwardly extending annular flange having a number of teeth 12 thereon.

The other clutch member 13 is attached to a support 14 which is attached to the shaft 3 by a pin 15. The clutch member 13 is provided with an inwardly extending annular flange of the same diameter as the annular flange of the clutch member 10. The entire edge of the flange on the clutch member 13 is provided with a series of teeth 16 adapted to be engaged by the teeth 12 to lock or close the clutch. The teeth on one of the clutch members are slightly larger than the teeth on the other clutch member; that is, assuming that there are 49 teeth of equal size and equally spaced on the clutch member 10, there may be 50 teeth of uniform size and uniformly spaced on the clutch member 13. Thus, it will be seen that all of the teeth on the clutch members cannot be simultaneously engaged, because the size and spacing of the teeth on one clutch member varies with respect to the size and spacing of the teeth on the coöperating clutch member, as will be understood by reference to the diagrammatic illustration in Fig. 5, and to the illustration of the clutch members in engagement with each other in Fig. 2. It will also be understood that very slight movement of one clutch member with respect to the other clutch member will be required in order to disengage any teeth which may be in engagement, and to engage other teeth with each other. In fact, by using a large number of teeth on the two clutch members only an imperceptible movement will be required, so that the paper can be adjusted almost to any precise line. Since the clutch member 13 is rigid upon the shaft 3 the said shaft and the platen thereon will be rotated by operation of any line spacing mechanism acting upon the wheel 5.

A sleeve 17 is slidably mounted upon the outer portion of the shaft 3 and supports a cylindrical case 18 inclosing the clutch members and protecting them from dirt and dust.

A number of arms 19 are attached to the case 18 and extend through notches or spaces formed in the clutch member 13, beyond the inner ends of the teeth 16 but normally out of contact with the clutch member 10. Outward movement of the sleeve 17 is prevented by the head of a screw 20 the shank of which is within the end of the shaft 3.

A knob 21 is attached to the sleeve 17 and constitutes a handle whereby the sleeve 17

may be forced inwardly on the shaft 3 to the position shown in Fig. 3. Thus, by pressing inwardly the knob 21 and the other parts controlled thereby the ends of the arms 19 will be brought into contact with the outer surface of the clutch member 10 and will press said clutch member inwardly against the tension of the spring 11, and disengage the teeth 12 from the teeth 16. The inward movement of the parts to open the clutch presses the edge of the case 18 against a beveled member, preferably a roller, on the lower arm of the bell crank 7, thereby firmly seating or locking the detent 6 in engagement with the line space wheel 5 and preventing any movement of said line space wheel while the platen and paper are being adjusted by turning the knob 21. Because of the large number of teeth, and the slight differential existing between the number and spacing thereof on the two clutch members the clutch members will engage in any of the adjustments to which the platen may be moved irrespective of the minute distance of such movement so long as such distance is no less than the difference in the differential compensator in the clutch.

It will be understood that any suitable actuating device may be employed to act upon the wheel 5 and move the paper in line spacing. In the "Dalton" adding machine, in connection with which I have illustrated my invention, there is a rock shaft 22^a (Fig. 1) which is rocked forward and back in recording operations. When the device is used upon the "Dalton" adding machine the rock shaft 22^a may be caused to actuate the line space mechanism consisting of a train of connections 23 arranged to operate a pawl 24 and cause said pawl to rotate the line space wheel and thereby the platen through the medium of the clutch mechanism above described. The writing line is represented by the lower edges of openings in the uprights 25 attached to the case of the machine.

It will be obvious that the invention may be employed in various types of recording machines and that it is by no means restricted to use upon any particular type of machines. Neither do I restrict myself to specific forms of the device, but—

What I claim and desire to secure by Letters Patent is:

1. In a recording machine, the combination with a platen, and a platen shaft, of a line spacing wheel mounted on said platen shaft, a toothed clutch member interlocked with and movable with respect to said wheel, a toothed differential clutch member arranged to engage said first-named clutch member in any one of various positions, a device for rotating the platen, and means controlled by said device for disengaging said clutch members.

2. In a recording machine, a platen arranged to hold paper, a shaft supporting said platen, a line space wheel loosely mounted on said shaft, a clutch member movable with said line space wheel, an annular series of teeth on said clutch member; a second clutch member, an annular series of teeth on said second-named clutch member to engage with said first-named clutch member in any one of various adjustments, means for rotating the platen, means controlled by said rotating means for disengaging said clutch members, and a detent device controlled by the disengagement of said clutch members to hold said line space wheel.
3. The combination with a platen arranged to hold paper, and a shaft holding said platen, of a line space wheel on said shaft, a detent device acting upon said line space wheel, a differential clutch device adjustable to hold said platen in any one of various selected adjustments with respect to said line space wheel, means for disengaging said clutch device and rotating said platen independently of said line space wheel, and means operated by said disengaging means to hold said detent device positively in engagement with said line space wheel.
4. The combination with a platen, a shaft for rotating said platen, a ratchet wheel loosely mounted on said shaft, and a detent device operating on said wheel, of a differential clutch member movable toward and away from said wheel, means preventing said wheel and said clutch member from rotating with respect to each other, a co-operating clutch member rigid with said shaft, a spring between said wheel and said first-named clutch member actuating said clutch member into engagement with said co-operating clutch member, and means operable to disengage said first-named clutch member from said second-named clutch member and to rotate said platen and said shaft, substantially as described.
5. The combination with a platen, a shaft for rotating said platen, a ratchet wheel loosely mounted on said shaft, and a detent device operating on said wheel, of a differential clutch operable to hold said platen in any one of various position with respect to said ratchet wheel, means for rotating said platen and shaft and releasing said ratchet wheel from said clutch, and means controlled by said releasing device for pressing said detent device positively in engagement with said ratchet wheel, substantially as specified.
6. The combination with a platen and a shaft for rotating said platen, of a ratchet wheel loosely mounted on said shaft, a differential clutch for locking said wheel in connection with said shaft, means for opening said clutch to release said wheel and said shaft from each other, and means actuated by said clutch opening means for positively preventing rotation of said wheel when said clutch is open.
7. The combination with a platen, and a shaft for rotating said platen, of a line space wheel loosely mounted on said shaft, a clutch device for locking said wheel and said shaft together, means for opening said clutch device to permit said shaft to rotate with respect to said wheel, and means actuated by said clutch opening means; device for positively preventing said wheel from rotating.
8. In a recording machine, the combination with a revoluble shaft, a platen, mounted on said shaft, a line space wheel loosely mounted on said shaft and arranged to operate said shaft and platen to feed the paper in line spacing, and a detent for holding said wheel, of a differential clutch device adjustable to lock said wheel and said shaft in any one of various positions whereby the platen may be adjusted to hold the paper in position to receive records on any selected line, a device for rotating the shaft and platen to adjust the paper in any desired position as aforesaid, and means controlled by said device for opening the clutch to press said detent positively against said wheel to prevent movement thereof.
9. The combination with a platen, a shaft for rotating said platen, a line space wheel loosely mounted on said shaft and operable to rotate said shaft and platen, differential clutch elements for locking said wheel and said shaft in any one of various selected positions, a manually engageable device for rotating the shaft and platen, means operative by said rotating means for releasing said clutch mechanism to permit the shaft and platen to rotate independently of said wheel, a detent pressed positively against said wheel by said releasing means and automatic means for engaging said clutch elements after said platen and shaft have been rotated with respect to said wheel.
10. The combination with a platen, a shaft for rotating said platen, a line space wheel for rotating said shaft and platen, differential clutch elements whereby said shaft and platen may be locked in any one of various selected adjustments with respect to said wheel, means whereby said clutch elements may be disengaged and said shaft and platen rotated with respect to said wheel, a device controlled by said means for positively preventing rotation of said wheel when said shaft and platen are rotated as aforesaid, and automatic means for engaging said clutch elements after said platen and shaft have been rotated to the desired adjustment with respect to said wheel.
11. The combination with a platen, a revoluble shaft on which said platen is mounted,

and a line space wheel mounted on said shaft and arranged to rotate said platen and shaft in their line space movements, of a differential clutch mechanism for locking said wheel 5 and shaft together in various positions intermediate of the line space movements, means for releasing said clutch mechanism, and means controlled by the release of the clutch mechanism to prevent movement of 10 said wheel, substantially as specified.

12. In a recording machine, the combination with a platen, and a line space wheel for actuating said platen in line spacing, of an annular series of teeth, means for preventing 15 relative rotation of said wheel with respect to said series of teeth, another annular series of teeth, a spring between said line space wheel and said first-named series of teeth pressing said teeth into engagement with 20 said second series of teeth, a device for rotating said platen, said device being movable toward said platen, and means operated by said device for disengaging said first-named teeth from said second-named teeth, substantially 25 as described.

13. In a recording machine, the combination with a platen, and a platen shaft, of a line space wheel loosely mounted on said shaft, a member interlocked with said wheel 30 and also loosely mounted with respect to said shaft, an annular series of teeth on said member, a support rigid on said shaft, a clutch member rigid on said support, an annular series of teeth on said second named 35 member formed differentially with respect to said teeth on said first named member, means for holding the teeth on said first named member in engagement with the teeth on said second named member, and means 40 for disengaging said teeth.

14. In a recording machine, the combination with a platen, and a platen shaft, of a member loosely mounted on said shaft, an annular series of teeth on said member, a 45 support rigid on said shaft, a clutch member attached to said support, an annular series of teeth on said second named member arranged differentially with respect to the teeth on said first named member, means for engaging the teeth on said first named member with the teeth on said second named member, and means for disengaging said teeth. 50

15. In a recording machine, the combination with a platen, a platen shaft, and a line 55 space wheel loosely mounted on said shaft, of a member loosely mounted with respect to said shaft, means for preventing said member from turning with respect to said wheel and permitting lateral movement of said 60 member with respect to said wheel, an annular series of teeth on said member, a second annular series of teeth rigid with respect to said shaft, means actuating said member toward said second series of teeth effectively

to engage the teeth on said member with said second series of teeth, and means for disengaging said teeth.

16. In a recording machine, the combination with a platen shaft, a ratchet wheel loosely mounted on said shaft, an annular 70 series of teeth loosely supported on said shaft, and means for preventing said ratchet wheel and said annular series of teeth from rotating with respect to each other, of a second annular series of teeth rigid on said 75 shaft, a spring for pressing said first-named teeth into engagement with said second-named teeth, and means for pressing said first-named teeth toward said ratchet wheel to disengage said teeth from said second-named teeth, said means being operable to rotate said platen independently of said first-named series of teeth, substantially as described.

17. In a recording machine, the combination with a platen shaft, a ratchet wheel loosely mounted on said shaft, an annular series of teeth movable toward and away from said ratchet wheel, and means preventing said ratchet wheel and said teeth 90 from revolving with respect to each other, of a second annular series of teeth rigid on said shaft, and a helical spring encircling and wholly supported by said shaft between 95 said ratchet wheel and said first named series of teeth, for the purpose specified.

18. In a recording machine, the combination with a platen shaft, a ratchet wheel loosely mounted on said shaft, an annular series of teeth loosely mounted on said shaft, a second annular series of teeth rigid on said shaft, and means for intermeshing said two series of teeth, of an actuating member, means controlled by said actuating member for disengaging said teeth, and means controlled by said member for holding said ratchet wheel against rotation. 105

19. In a recording machine, the combination with a platen shaft, a ratchet wheel loosely mounted on said shaft, and differential clutch devices for locking said ratchet wheel with respect to said shaft, of a manually engageable member for rotating said shaft, means controlled by said member for disengaging said clutch devices and releasing said ratchet wheel with respect to said shaft, and a device controlled by said member for positively holding said ratchet wheel against rotation when said shaft is rotated by said member during disengagement of 115 said clutch devices.

20. In a recording machine, the combination with a platen shaft, and a ratchet wheel loosely mounted on said shaft, of clutch devices for locking said ratchet wheel upon 120 said shaft, a manually engageable device for rotating said shaft, and means controlled by said device for positively holding said

ratchet wheel stationary during rotation of said shaft by said device.

21. In a recording machine, the combination with a platen shaft, and a ratchet wheel loosely mounted on said shaft, of clutch devices for locking said ratchet wheel upon said shaft, manual means for rotating said shaft, and elements controlled by said manual means for positively holding said ratchet wheel stationary during rotation of said shaft.

22. In a recording machine, the combination with a platen shaft, and a ratchet wheel loosely mounted on said shaft, of clutch devices for locking said ratchet wheel upon said shaft, manual means for releasing said clutch device, and elements controlled by said manual means for positively holding said ratchet wheel from rotation.

23. In a recording machine, the combination with a platen shaft and a ratchet wheel loosely mounted on said shaft, of clutch devices for locking said ratchet wheel upon

said shaft, a manually engageable device for rotating said shaft, means controlled by said device for releasing said clutch devices, and means controlled by said device for positively holding said ratchet wheel stationary during rotation of said shaft by said device.

24. In a recording machine, the combination with a platen shaft and a ratchet wheel loosely mounted on said shaft, of clutch devices for locking said ratchet wheel upon said shaft, a manually engageable device supported by said shaft and movable axially thereon, means controlled by said device for releasing said clutch devices, and means controlled by said device for positively holding said ratchet wheel stationary.

In witness whereof, I have signed this 40 specification in the presence of two subscribing witnesses.

HARRY LANDSIEDEL.
